UNITED STATES PATENT OFFICE.

TOM I. SHUTTLEWORTH, OF AMSTERDAM, NEW YORK, ASSIGNOR OF ONE-HALF TO JOHN BURT, OF PHILADELPHIA, PENNSYLVANIA.

CUT PILE FABRIC.

SPECIFICATION forming part of Letters Patent No. 391,652, dated October 23, 1888.

Application filed February 11, 1888. Serial No. 263,741. (No specimens.)

To all whom it may concern:

Be it known that I, TOM I. SHUTTLEWORTH, a citizen of the United States, and a resident of Amsterdam, Montgomery county, New York, have invented certain Improvements in Cut Pile Fabrics, of which the following is a specification.

My invention consists of a certain improvement in that class of pile fabrics which are woven double and subsequently cut apart, the object of my invention being to facilitate the weaving of such double fabric, and to produce a fabric having a firm back and close pile with the use in each fabric of a less number of figuring warp-threads than are employed in making the usual single fabric. This object I attain in the manner hereinafter set forth, reference being had to the accompanying drawings, in which—

Figure 1 is an exaggerated diagram illustrating a section of my improved fabric, the section being taken on a line transversely to the warp. Figs. 2 and 3 are longitudinal sections, respectively, on the lines 1 2 and 3 4, Fig. 1; and Fig. 4 is a view illustrating a slightly modified form of the fabric.

In the present method of producing figured cut pile fabrics by weaving the fabric double, carrying the figuring warp-thread across from one backing to the other, and then severing these figuring warp threads midway between the two backings, it is the usual custom to distribute the figuring warp-threads in each fabric uniformly from one side of the fabric to the other—that is to say, there will be in both the upper and lower sheds a certain proportion of figuring warp-threads for each dent of the reed, and where stuffing-warps are used the dents are unduly crowded and free shedding

of the warps is interfered with. I desire to overcome this objection, and yet adhere to the plan of weaving the fabric double and then cutting it apart, so as to produce a fabric having a firm body and a sufficiently close pile with considerably less than the amount of figuring-warp now used in making a cut pile fabric by the usual plan of weaving the fabric with loops and then cutting the latter. I therefore alternate the disposal of the sets of figur-

ing warp-threads in the two sheds. Thus, for example, the upper shed may have sets of figuring warp-threads disposed in the dents 1 3 5 7, &c., of the reed, there being no figuring warp-threads in the dents 2 4 6 8, &c., while in the lower shed the disposal of the sets of figuring warp threads is reversed, said sets occupying the dents 2 4 6 8, &c., of the reed, while there are no figuring warp-threads in the dents 1 3 5 7, &c., the vacant dents of the reed in each shed being occupied by the stuffing-warps, which therefore do not in any way interfere with the free shedding of the figuring-warps in the other dents of the reed. The consequence of this is, that viewing the fabric transversely, as in Fig. 1, the pile is formed alternately by a thread drawn down from the upper backing and looped into the lower backing, and by a thread drawn up from the lower backing and looped into the upper backing, and when the fabric is severed the pile will be formed by longitudinal rows of tufts projecting upward from the backing, the tufts of every other row consisting of the projecting ends of figuring warp-threads extending from end to end of the fabric and buried in the backing, while the tufts of the alternate rows consist of the projecting ends of independent loops simply tied into the backing by the filling-threads, the stuffing-warps being disposed alongside of these rows of independent loops, so as to provide for the proper stiffening of the fabric.

In the drawings, the letters *a* represent the figuring warp-threads, *b* the binding-warps, *d* the stuffing-warps, and *f* the binding-wefts, three of these being used in the present instance for each transverse row of pile-loops, although more or less than three binders may be used, if desired.

In carrying out my invention it is not absolutely necessary that the tufts derived from the threads buried in the backing and the tufts formed by the independent loops should be in single rows, as a series of rows of tufts formed by independent loops may alternate with a series of rows of tufts derived from the buried warps. (See Fig. 4, for instance.) Where two stuffing-warps are used for each row of tufts formed by the independent loops, one of said

warps may be on each side of the row of tufts, as shown at *d'* in Fig. 4.

Having thus described my invention, what I claim, and desire to secure by Letters Patent, is—

A cut pile fabric in which binding warps and wefts and stuffing-warps forming a backing are combined with a pile composed of longitudinal rows of projecting tufts, some of said rows consisting of tufts drawn up from sets of figuring-warps buried in the backing, and al-

ternate rows consisting of tufts formed by single independent loops tied into the backing and disposed by the side of one or more stuffing-warps, all substantially as specified.

In testimony whereof I have signed my name to this specification in the presence of two subscribing witnesses.

TOM I. SHUTTLEWORTH.
